UNITED STATES PATENT OFFICE.

KENNETH B. MARTIN, OF SPRINGFIELD, MISSOURI.

SWIMMING DEVICE.

Application filed October 22, 1926. Serial No. 143,423.

My invention relates to improvements in swimming devices of that class to which buoyant garments belong, and which consists in the combinations, constructions and arrangements herein described and claimed.

An object of the invention is the provision of a swimming device which can be worn comfortably and without interference with the bodily movement of the wearer and which will support the wearer against sinking in water in a position suitable for swimming or for rest.

A further object of the invention is the provision of a swimming device of the character described that can be adjusted to fit a wearer of any one of a plurality of different sizes and which also can be adjusted on the body of the wearer so as to float the body of the wearer in the water.

20 A still further object of the invention is the provision of a swimming device of the character described that is light in water, capable of being folded to take up but little space when not in use, attractive in appearance, economical to manufacture, and thoroughly practical commercially.

Other objects and advantages of the invention will be apparent from the following description considered in conjunction with the accompanying drawings, in which:

Figure 1 is a perspective view of a swimming device embodying the invention applied in position on the body of the wearer.

Figure 2 is a plan view of the members of the swimming device as they appear when spaced from each other.

Figure 3 is a section substantially along the line 3—3 of Figure 2.

Figure 4 is a front view of a modified form of front member which can be used in the swimming device.

The improved swimming device preferably comprises a front buoyant or float member generally indicated at 1, and a rear float member generally indicated at 2. The front float member is substantially of inverted V-shape and comprises a pair of downwardly divergent branches 3 which are connected at their upper ends by an upper or web portion 4.

The back float member 2 may be substan-

tially rectangular in longitudinal sectional configuration, as clearly shown in Figure 2, and is of sufficient length to extend on the back of a wearer substantially for the full 55 length of the back portion of the wearer, and also may be substantially as wide as the back portion of the body of the wearer. The back float member 2 has a pair of shoulder straps 5 at its upper end which are adapted 60 to be extended forwardly across the shoulders of the wearer and which have fastening elements 6 adjacent to their extremities for engagement with co-operating fastening elements 7 on the upper end portions of the branches 3 of the front float member. It will be noticed that there are a plurality of longitudinally spaced fastening elements 7 on the upper end portion of each of the branches 3 of the front float member so that 70 the shoulder straps 5 and the branches of the front float member may be adjustably connected with each other. The co-operative fastening elements 6 and 7 may be of any suitable known construction and may comprise snap fasteners. The adjacent edges of the shoulder straps 5 are co-operatively curved at their junctures with the upper end of the back float member so as to produce a concavely curved edge at 8, thus allowing 80 ample clearance for the neck of the wearer. The upper edge of the web portion 4 of the front float member also may be concavely curved at 9, to afford ample clearance for the front portion of the neck of the wearer 85 when the device has been adjusted to its smallest possible size, that is, when the fastening elements 6 have been attached to the lowermost fastening elements 7.

The branches 3 will diverge from the lower end of the upper portion of the front member of the device toward the lower side portions of the body of the wearer, as shown in Figure 1, when the front and rear buoyant members are supported on the body of the 95 wearer by the shoulder straps, as shown in Figure 1. The lower end portions of the branches 3 of the front float member are connected by a tie strip 10 which extends across the stomach of the wearer and limits the 100 spreading of the lower end portions of the branches and prevents the lower end portions

of the branches from being forced rearwardly beyond the sides of the wearer when the device is in use in the water. An adjustable connection between the lower end 5 of the rear float member 2, and the upper or web portion of the front float member 1, comprises a strip 11 which is attached at one end to the lower end portion of the rear float member 2 intermediate the 10 width of the rear float member. The strip 11 is adapted to be extended under the crotch and upwardly at the front of the body of the wearer, as shown in Figure 1, and has a hook 12 at its extremity which is adjustably engageable with a chain 13. The chain 13 is attached at its upper end to the web portion 4 of the front float member at the outer side or front face of the latter. The adjustment of the connection between the 15 members 11 and 13 determines the longitudinal adjustment of the front and rear members on the body of the wearer, and the center of buoyancy of the device as a whole, thus can be adjusted so that the wearer of 20 the device will be supported in position for swimming in the water and so that the tendency of the body of the wearer to assume an upright position or inverted position in the water will be overcome. The adjustment 25 of the members 11 and 13 with respect to each other, also varies the size of the device.

The front and rear float members are additionally connected with each other and secured 30 in place on the body of the wearer by a pair of strips 14 and 15, respectively, which have end portions secured to the outer side 35 portions of the branches 3 of the front float member, at points somewhat nearer the lower ends of the branches 3 than the upper ends of said branches. The straps 14 and 15 cross each other at the back of the wearer and extend across the rear float member 2, the free ends of the straps 14 and 15 being 40 extended across the branches 3 of the front float member and being adjustably connected 45 with each other at the front of the wearer by suitable fastening devices such as indicated at 16 in Figure 1. These straps 14 and 15 thus secure the approximate middle portions 50 of the front and rear float members to the body of the wearer substantially at the waist line of the wearer.

Each of the float members may comprise a 55 water proof casing or covering fabric, such as indicated at 17, and a filling 18 of cork or any other substance that is lighter than water. The space within the casing 17 of the rear float member may be divided longitudinally 60 by a row of stitching 19 and the longitudinal compartments of the rear float members somewhat flattened or substantially elliptical in cross section as shown. The rear float member also may have a transverse 65 row of stitching as indicated at 20 which

will divide the longitudinal compartments transversely. The rows of stitching 19 and 20 provide fold lines for the rear float member so that it can be folded to compact form.

The front float member may have the 70 spaces within the casing of the branches thereof divided transversely intermediate their lengths by the transverse rows of stitching 21. Transverse rows of stitching 22 also may be provided across the upper 75 end portions of the branches 3 of the front float member adjacent to their juncture with the web portion 4 of the front float member. The front float member may be folded along the rows of stitching 21 and 22 and the portions of the branches 3 below the rows of stitching 22 may be flattened or substantially elliptical in cross sectional configuration while the portion of the front float member above the rows of stitching 22 may 80 be flattened somewhat to fit snugly against the upper part of the front portion of the body of the wearer.

The straps 14 and 15 may extend across the back float member in the groove that is 85 produced by the transverse row of stitching 20 and across the front float member in the grooves which are produced by the transverse rows of stitching 21, whereby the straps 14 and 15 will be held against slipping 90 downward on the float members.

The front and back float members also may be maintained in shape and the filling substances secured to the covering members thereof by strings extending therethrough at 95 intervals as in an ordinary cotton bed mattress.

From the foregoing description of the various parts of the device, the operation thereof may be readily understood. The device 105 will support the body of the wearer in the water so that the center of buoyancy will not have a tendency to cause the user of the device to assume an upright position in the water with his feet down, or an inverted 110 position in the water.

The arms and legs of the wearer of the device are unnumbered and the device is so well balanced when in use, that the wearer may remain in a position to rest while afloat, 115 or may freely use his limbs as required in swimming. The device also can be worn comfortably out of the water and when folded will take up but relatively little space and therefore can be carried conveniently 120 from place to place. It will be noticed that relatively few fastening devices are required to hold the members of the device in adjusted positions on the body of the wearer.

The front float member may be formed to 125 comprise relatively short branches 3^a and a relatively long upper end portion or web 4^a as shown in Figure 4. The operation of the front float member shown in Figure 4 is identical in essential respects with the opera- 130

tion of the front float member 1, which may be replaced by the front float member exhibited in Figure 4 if desired.

Obviously the invention is susceptible of embodiment in forms other than that which is illustrated in the accompanying drawings and I therefore consider as my own all such modifications and adaptations thereof as fairly fall within the scope of the appended 10 claims.

What I claim is:

1. A swimming device comprising a front float member and a rear float member, said front float member including a pair of downwardly and laterally diverging branches, shoulder members adjustably connecting the upper ends of said float members for supporting said float members on the body of the wearer, and adjustable means encircling 20 the body of the wearer and securing said front and rear float members to the body of the wearer.

2. A swimming device comprising a rear float member and a front float member, said 25 front float member including a pair of downwardly and laterally diverging branches, a pair of straps at the upper end of said rear float member adapted to extend across the shoulders of the wearer, cooperative fastening 30 elements at the extremities of said shoulder straps on the upper end portion of said front float member, adjustable means extending under the crotch of the wearer and connecting the lower end of said rear 35 float member with said front float member, and other fastening means encircling the body of the wearer and tending to hold said front and rear float members clamped against the body of the wearer.

3. A swimming device comprising a rear float member adapted to be positioned against the back of the body of the wearer, straps at the upper end of said rear float member adapted to extend across the shoulders of a wearer, a front float member having a pair of downwardly and laterally divergent branches, cooperative fastening elements on the upper ends of the portions 45 of said front float member and on the adjacent edge portions of said shoulder straps, adjustable means extending under the crotch of the wearer and connecting the lower end portion of said rear float member and the upper portion of said front float member, and a tie member connecting the lower ends 50 of the branches of said front float member and extending across the front of the body of the wearer.

4. A swimming device comprising a rear 60 float member adapted to be positioned against the back of the body of the wearer, straps at the upper end of said rear float member adapted to extend across the shoulders of a wearer, a front float member having a pair of downwardly and laterally di-

vergent branches, cooperative fastening elements on the upper ends of the portions of said front float member and on the adjacent edge portions of said shoulder straps, a chain attached at one end to the front float member at the juncture of the upper ends of the branches of said front float member, a strap attached to one end to the lower end of the rear float member and adapted to extend under the crotch of the wearer of said last 70 named strap having fastening elements at its extremity adjustably engageable with said chain, a tie strap connecting the lower ends of the branches of said front float member, and a pair of cooperative binding straps having their remote ends attached to the outer sides of the branches of said front float member and being adapted to be crossed at the back of the wearer against the back float member and then extended to the front 75 of the wearer across the branches of the front float member and adjustably connected with each other at the front of the wearer.

5. A swimming device comprising a plurality of buoyant members, each comprising a casing of flexible water-proof material and a filling of substance lighter than water, said buoyant members having rows of stitching connecting opposite portions of the casing, and defining lines on which said buoyant 90 members can be folded, the members at one side of the line of fold being divergent laterally in an outward direction therefrom.

6. A swimming device comprising a rear float member substantially rectangular in longitudinal sectional configuration, a front float member having a pair of downwardly divergent branches, adjustable fastening means connecting said float members and maintaining said float members in place on the body of the wearer, said rear float member having a longitudinal row of stitching thus dividing said rear float member longitudinally into two sections, each of which is substantially elliptical in cross section, and the branches of said front float member also being substantially elliptical in cross sectional configuration.

7. A swimming device comprising a rear float member substantially rectangular in longitudinal sectional configuration, a front float member having a pair of downwardly divergent branches, adjustable fastening means connecting said float members and maintaining said float members in place on the body of the wearer, said rear float member having a longitudinal row of stitching thus dividing said rear float member longitudinally into two sections, the sections of the rear float member and the branches of said front float member being substantially elliptical in cross sectional configuration, the portion of the front float member at the juncture of said branches being relatively flat.

8. A swimming device comprising a rear float member adapted to be positioned against the back of a wearer, a front float member, straps connecting the upper ends of said float members and adapted to extend across the shoulders of a wearer, said float members being downwardly and laterally diverging and having transverse grooves in

their outer faces, and straps for encircling the body of the wearer and said float members for securing said float members to the body of the wearer, said straps being engageable with said transverse grooves, whereby the straps will be prevented from slipping downward on the float members. 10
